UNITED STATES PATENT OFFICE.

SILLUS DA COSTA NEWMAN, OF JELlico, TENNESSEE.

MONEY-DRAWER ALARM.

No. 884,843.

Specification of Letters Patent. Patented April 14, 1908.

Application filed June 3, 1907. Serial No. 377,085.

To all whom it may concern:

Be it known that I, SILLUS DA COSTA NEWMAN, a citizen of the United States, residing at Jellico, in the county of Campbell and State of Tennessee, have invented certain new and useful Improvements in Money-Drawer Alarms, of which the following is a specification.

My invention relates to electric alarms for money drawers and has for its object to provide, first, a retracting spring for the money drawer that at the same time serves as a part of the circuit for the electric alarm, and, secondly, a construction of contacts whereby a person familiar therewith may give a predetermined signal in opening the drawer that would not ordinarily be given by an unauthorized operator of the drawer.

These objects I accomplish in the manner and by the means hereinafter described and claimed, reference being had to the accompanying drawing, in which:

Figure 1 is a vertical sectional view of a drawer and its casing provided with my improved construction. Fig. 2 is a top plan view of the same, the top of the casing being removed. Fig. 3 is a view similar to Fig. 1, illustrating a modified construction.

Similar numerals of reference denote, as far as possible, corresponding parts in the several views.

In the said drawing the reference numeral 1 denotes the drawer casing, and 2 the drawer sliding therein. Passing through the rear wall of said casing is a bolt 3, terminating in a binding post 4 at its outer end, and at its inner end having a plate 5 and a grooved projection 6, adapted to receive one end of a coiled spring 7, which may be soldered thereto, said spring being similarly attached at its other end to a grooved projection 8 fixed to a plate 9 that is in turn fixed to a bolt 10 passing through the rear wall of the drawer 2 and screw-threaded to receive a retaining nut 11.

Running from one pole of a suitable electric battery 12 is a wire 13 that leads through a bell 14 to the binding post 4, the other pole of said battery being connected by wire 15 to a metallic plate 16 fixed in the bottom wall of the casing 1 and terminating a short distance from the rear wall thereof, as shown.

Mounted exteriorly on the rear wall of the drawer 2 is a plate 17, through which the bolt 10 passes to form an electrical connec-

tion, said plate being upturned at its lower end at 18 and in sliding contact with the bottom wall of the casing 1 and with the plate 16 thereof while passing thereover, it being understood that said plate 10 lies in the path of travel of the plate 17.

From the above description it will be understood that the spring 7 tends to retract the drawer 2 to its innermost or closed position, in which position the lower end 18 of plate 17 is out of contact with plate 10, thus breaking the electric circuit. But when the drawer is pulled out against the tension of spring 7 a sliding contact at once ensues between the lower end 18 of plate 17 and the plate 10, thus completing the electric circuit which passes through spring 7, and sounding the bell 14, which will continue to ring so long as the drawer is open.

In the modified construction shown in Fig. 3, instead of employing a single contact plate 16 I provide a series of separate plates 19, each electrically connected with the wire 15, as shown, the result being that as the drawer 2 is pulled out a series of contacts will be successively made and broken, according to the number of separate plates 19 employed. By locating one of the plates 19 near the outer limit of movement of the drawer 2 I provide means whereby an authorized operator can indicate his use of the drawer by opening the same to the fullest extent, thereby giving two rings followed after an interval by a third ring. An unauthorized operator would not take the trouble to open the drawer to this extent, particularly against the tension of spring 7, and would thus give but two rings, thereby indicating tampering with the drawer.

Having thus described my invention, what I claim as new and desire to secure by Letters Patent, is:

1. In an electric drawer alarm, a drawer, a drawer support, an electric circuit, an alarm in said circuit, a plate fixed in the support and connected with one pole of said circuit, a contact plate fixed to said drawer and connected with the other pole of said circuit, and a spring permanently connecting said drawer and support and forming part of said circuit.
2. In an electric drawer alarm, a drawer, a drawer support, an electric circuit, an alarm in said circuit, and a series of independent contacts in said circuit between said drawer and support each forming part of said circuit.

and adapted to be successively closed as said drawer is opened.

3. In an electric drawer alarm, a drawer, a drawer support, an electric-circuit, an alarm in said circuit, a series of contacts in said support each forming part of said circuit, a contact plate on said drawer, and a retracting spring connecting said drawer and support and forming part of the electric circuit

and in electrical contact with said drawer 10 contact plate.

In testimony whereof I affix my signature, in presence of two witnesses.

SILLUS DA COSTA NEWMAN.
